UNITED STATES PATENT OFFICE.

WILLIAM M. WHEILDON, OF ASHLAND, MASSACHUSETTS, ASSIGNOR TO EDWARD H. ANGIER, OF FRAMINGHAM, MASSACHUSETTS.

COLLAPSIBLE CONTAINER.

1,278,806.

Specification of Letters Patent. Patented Sept. 10, 1918.

Application filed April 26, 1917. Serial No. 164,720.

To all whom it may concern:

Be it known that I, WILLIAM M. WHEILDON, a citizen of the United States, and a resident of Ashland, in the county of Middlesex and State of Massachusetts, have invented an Improvement in Collapsible Containers, of which the following description, in connection with the accompanying drawings, is a specification, like characters on the drawings representing like parts.

This invention relates to containers and its object is to provide a container which is collapsible so that it may be folded into small space when not in use.

15 My invention will best be understood by reference to the following description of one embodiment of my invention taken in connection with the accompanying drawings, wherein—

20 Figure 1 is a plan of the container distended and ready for use;

Fig. 2 is a similar view showing the container partially closed;

Fig. 3 is a section on line 3—3 of Fig. 1; 25 and

Fig. 4 is a side view of the container.

Referring particularly to Fig. 1 the container which I have chosen as illustrating my invention is similar to a bucket and may include a flexible bag 5 of cloth, waterproof paper or similar material adapted to be suspended between two side bars 7, 7. The two side bars 7, 7 are adapted to be placed side by side when the bucket is not in use, as will readily be understood from an inspection of Fig. 2 which shows the bucket partially closed and the bag 5 may be wrapped around them to form a package of small breadth and thickness.

40 Suitable means are provided connecting the two side bars 7, 7 for holding the bucket in its distended position and for facilitating the handling thereof. I here show a brace connecting the lower ends of the bars 7, 7 in the form of two toggle links 9, 9

45 pivoted together centrally between the side bars at 11 and to the lower ends of each side bar at 13. When the bucket is not in use the links will fold and lie side by side

50 with the side bars 7, as will be clear from an inspection of Fig. 2 and they may readily be drawn down into the position shown in Fig. 1 to open out the bag 5, brace apart the side bars 7 and also to provide a con-

venient handle by which the bottom of the 55 bucket may be lifted and tilted.

Suitable stop means are provided to prevent the links 9 from moving out beyond the position illustrated and I have here shown co-operating surfaces 15 on the links 60 and the side bars, forming stops to limit movement of the links 9 about the pivot 13. It is preferable to have the limiting means as here illustrated at the joint between the links and the side bars as the person opening the bucket is then less likely to catch some part of his hand in the joint than would be the case if the stop were placed at the joint 11.

55 A suitable handle or bail is also provided for the bucket, adapted to extend between the upper ends of the side bars 7 and to fold side by side with them when the bucket is collapsed. I have herein shown toggle links 17 similar to the links 9 and provided 75 with stop means 19 similar to the means 15 already described. It will be understood that the links 17 will ordinarily be somewhat longer than the links 9, to provide a flaring shape for the bucket. Furthermore, 80 the links 17 are arranged to pass center position and take the position shown in Fig. 1, so as to provide a handle for the bucket higher at the center than at the sides.

85 As seen most clearly in Fig. 4, the ends of the side bars 7 may be offset to provide for an easy clearance of the toggle links and the main portions of the bars.

90 It will be clear from reference to Fig. 1, that the several links 7, 9 and 17 form a frame which may be collapsed so that the entire bucket may be folded into small space, or opened out to provide an open frame between opposite sides of which is suspended the bag 5 which forms a fluid container. 95 It is, of course, obvious that the bag 5 is of such size as to provide for a certain fullness when the parts are in the position shown in Fig. 1. The stop means 15 and 19 keep the frame in shape and when the container is suspended by the handle formed by the links 17 both ends of the side bars will be braced apart to prevent the weight of water or other material in the flexible bag from drawing them together and in particular inward pivoting movement of the side bars 7 on the pivots 13 is prevented so that the upper part of the bucket will not collapse by 100

2 drawing together of the two points by which it is suspended.

The flexible bag 5 may be secured to the side bars 7 in any suitable manner. In Fig. 5 3 I have shown the intermediate parts of these bars as of channel form and the edge 21 of the bag, which herein is provided with a sealed edge, is inserted between the flanges of the channel. Holding means such as 10 split rivets 23 may be passed through the flanges and through the edge 21 to hold the bag 5 in place. The rivets may be formed of soft brass or similar material so as to be easily manipulated to permit the insertion 15 of a new bag in the frame without special tools whenever necessary.

Having thus described in detail one suitable embodiment of my invention, what I claim and desire to secure by Letters Patent is:—

1. A collapsible container comprising a substantially plane frame having opposed side bars, toggle links connecting said bars at top and bottom, means to limit movement 25 of said links in one direction and a flexible, open-topped bag having its side portions secured to said bars.

2. A collapsible container as defined in claim 1 wherein the limiting means comprise 30 surfaces arranged for interlocking engagement at the junctions of the side bars and the links.

3. A collapsible container comprising side members, a flexible bag extending between 35 them, collapsible bracing means between the lower ends of said members, pivoted links between the upper ends and means for limiting the movement of said links providing for positioning them in bail-like form 40 across the top of the bag to provide a handle for the container.

4. A collapsible container comprising a substantially plane frame having opposed side bars, a collapsible brace between the 45 lower ends of said side bars which may be collapsed to permit them to lie side by side and a handle or bail for bridging the upper ends of said bars arranged to fold to lie substantially in line therewith, and a flexible 50 open-topped bag having its side portions secured to said bars.

5. A collapsible container comprising a substantially plane frame having opposed side bars, a collapsible brace between the 55 lower ends of said bars which may be col-

lapsed to permit them to lie side by side, a handle or bail extending between the upper ends of said bars and a flexible open-topped bag having its side portions secured to said bars.

60

6. A device of the class described comprising a set of substantially coplanar pivoted links collectively expandable to provide an open frame, means to limit their pivoting movement whereby to control the 65 form of such frame and a container arranged for attachment to opposite sides of the frame to lie in the plane thereof.

7. A device of the class described comprising side bars and a bottom brace to the 70 extremities of which said bars are hinged and adapted to form a substantially plane, U-shaped frame, a flexible bag having side portions secured to the said side bars or arms of the U, means for connecting the 75 upper ends of the bars to provide a flexible handle and means to limit inward swinging of the bars when the device is suspended by the handle.

8. A device of the class described comprising side bars, a bottom brace to the extremities of which said bars are hinged, said parts being arranged for folding to lie side by side, a flexible bag having its side portions secured to said bars and adapted to 85 be wrapped about them when folded, means for connecting the upper ends of the bars to provide a flexible handle and means to limit inward swinging of the bars when the device is suspended by the handle.

90

9. A collapsible container comprising side members, a bottom brace to the extremities of which said members are hinged, a flexible bag having side portions secured to said members, means for connecting the 95 upper ends of said members to provide a handle and means rendered effective by tension on said handle to limit inward swinging of said members.

10. A device of the class described comprising a pair of channelled side bars, a bag having its side edges received between the flanges thereof, a brace between the lower ends of said bars arranged to be folded relatively thereto and a handle between the 105 upper ends of said bars arranged to be folded relatively thereto.

In testimony whereof, I have signed my name to this specification.

WILLIAM M. WHEILDON.
